US00D826870S

(12) **United States Design Patent** (10) **Patent No.:** **US D826,870 S**
(45) **Date of Patent:** **** Aug. 28, 2018**

(54) **CONTROL MODULE**

(71) Applicant: **Steelcase Inc.**, Grand Rapids, MI (US)

(72) Inventors: **Colin Cote**, Grand Rapids, MI (US);
David Craig Cooper, Grand Rapids, MI (US); **Rachel Neiman**, Grand Rapids, MI (US)

(73) Assignee: **Steelcase Inc.**, Grand Rapids, MI (US)

(**) Term: **15 Years**

(21) Appl. No.: **29/606,850**

(22) Filed: **Jun. 8, 2017**

(51) LOC (11) Cl. **13-03**

(52) U.S. Cl.

USPC **D13/164**

(57) **CLAIM**

We claim the ornamental design for a control module, as illustrated and described.

DESCRIPTION

FIG. 1 is a front perspective view of a control module; FIG. 2 is a bottom perspective view of the control module of FIG. 1;

FIG. 3 is a front view of the control module of FIG. 1; FIG. 4 is a rear view of the control module of FIG. 1; FIG. 5 is a right side view of the control module of FIG. 1; FIG. 6 is a left side view of the control module of FIG. 1; FIG. 7 is a top view of the control module of FIG. 1; and, FIG. 8 is a bottom view of the control module of FIG. 1. The dashed lines are for purposes of illustrating environmental structure and form no part of the claimed design.

1 Claim, 3 Drawing Sheets
